UNITED STATES PATENT OFFICE.

ALVIN CHARLES STIEFEL, OF HOUMA, LOUISIANA.

HAND-PUMP.

1,108,637.

Specification of Letters Patent. Patented Aug. 25, 1914.

Application filed August 21, 1913. Serial No. 785,929.

To all whom it may concern:

Be it known that I, ALVIN C. STIEFEL, a citizen of the United States, and a resident of Houma, in the parish of Terrebonne and 5 State of Louisiana, have invented a new and useful Improvement in Hand-Pumps, of which the following is a specification.

My invention is an improvement in hand pumps, and has for its object to provide a 10 pump of the character specified, for use in transferring liquid from one receptacle to another, or for bailing out boats and the like, wherein a light, compact and easily transported device is provided, capable of being 15 held in one hand and operated by the other, or in any other suitable manner.

In the drawings:—Figure 1 is a side view of the improved pump with parts in section, Fig. 2 is a longitudinal section, Fig. 3 is a 20 section on the line 3—3 of Fig. 4, Fig. 4 is a section on the line 4—4 of Fig. 1, looking in the direction of the arrows, Fig. 5 is a top plan view of the lower valve and its support, and Fig. 6 is a transverse vertical section of the lower end of the pump and the 25 lower valve.

The present embodiment of the invention comprises a casing 1 of cylindrical form, having its lower end open as indicated, and 30 the casing is provided with an annular series of openings near the open end, the said openings being arranged in a sleeve, and being rectangular in form in the present instance. The opposite or upper end of the 35 casing 1 is flaring, as indicated at 4, and the said flaring portion is provided with an opening 5, and a delivery elbow 6 is connected to the flaring portion of the casing at the opening. The outlet 7 of the delivery elbow 40 is arranged to extend toward the closed end as shown, and a cylindrical plunger rod 8 is arranged within the casing. The plunger rod 8 is provided at its upper end with a cross head or handle 9, and the lower end of 45 the said plunger rod is beveled on each side to a point, as shown at 10. The plunger rod 8 is of a length to extend from above the upper or flaring end of the casing, to near the bottom thereof, and the plunger or piston is 50 connected with the lower end of the said plunger rod. The piston is composed of a ring 11 of wire or the like, of an external diameter to fit within the casing 1. Arms 12 and 13 are provided for connecting the ring 55 with the plunger rod 8. The arm 12 is integral with the ring, the ring being formed by bending a wire or rod to form the ring, and one of the ends of the wire or rod is bent upwardly to form the arm 12. The said arms 12 and 13 are bent inwardly toward 60 the plunger rod, a short distance above the ring, and the said arms are secured to the plunger rod, by means of staples 14 or the like. Preferably the plunger rod, which in the present instance, is of wood, is grooved 65 longitudinally, to receive the portions of the arms 12 and 13 that lap upon the said plunger rod. The arm 13 is shaped like the arm 12, and at its lower end the said arm is bent angularly diametrically of the ring and of 70 the casing 1, to form a lug 15 lying above the ring 11.

A valve is supported by the lug 15, the said valve consisting of two semi-circular flaps or leaves 16 and 17. One of the leaves 75 16 is provided with a pair of aligned spaced bearings 18; the leaf 17 is provided with a single bearing 19, and the bearings 18 and 19 engage the lug 15, to hinge the sections of the valve directly above the ring. Normally the edges of the sections 16—17 of the 80 valve rest upon the ring and are supported thereby in horizontal position and in the same plane. A sleeve 20 is arranged in the casing at the lower end thereof, and the said 85 sleeve supports the foot valve. The sleeve 20 is provided with an annular series of openings 21, and the upper end of the sleeve is cut away from each side toward the center. A rod or pivot pin 22 is arranged 90 transversely of the sleeve at the center of the said cutaway portion, for supporting a sectional valve consisting of flaps 23 and 24, and the said flaps are hinged to the rod or pivot pin. The flaps are semi-circular, and 95 the flap 23 is provided at the center of its straight edge with a single bearing 25, for engaging the rod, while the flap 24 is provided with a pair of aligned spaced bearings 26 at its straight edge engaging the rod on 100 opposite sides of the bearing 25. In forming the sleeve 20, the side wall is cut-away from opposite sides inwardly and downwardly, the cuts meeting on a diameter of the sleeve, and the pin 22 is arranged at the 105 deepest portion of the cut, that is, at the diameter where the cuts meet.

The flaps or sections of the valve rest upon the inclined upper end of the sleeve, so that both flaps incline upwardly toward their 110 free edges. A portion of the material of the sleeve at each end of the pivot pin is

left, as indicated at 27, to form a stop for preventing disengagement of the pivot pin and also for limiting the upward movement of the flaps of the valve. The free ends of the 5 lugs 27 are bent inwardly as shown in Fig. 5 to over-lie the bearings 26. When the flaps are raised by the in-rushing water they will strike the lugs 27 before they reach a vertical position, thus insuring the proper closing 10 of the flaps on the downward movement of the plunger. The upper ends of the rods 12 and 13 are as before stated, arranged within grooves on the plunger and the extremities of the said rods are bent laterally 15 inward and driven into the material of the plunger as indicated at 28 in Fig. 1.

In operation, the lower end of the casing is introduced into the liquid to be transferred and by means of the handle 9, the 20 plunger rod and plunger are reciprocated. On the up stroke, the valves 16 and 17 hold their position in contact with the ring, and the liquid is drawn into the lower end of the casing, lifting the flaps 23—24 of the 25 foot valve. On the down stroke, the liquid in the casing is prevented from passing out by the closing of the said valve sections, and the sections 16 and 17 of the plunger valve are lifted, and the liquid flows above the 30 plunger or piston. A continuation of the reciprocating movement of the plunger rod will finally fill the casing with liquid, until it reaches the flaring portion 4 of the casing and flows out through the discharge elbow 35 6. On account of the large relative diameter of the plunger rod, there is but little space for the liquid in the upper part of the casing, and a few strokes of the plunger will cause the liquid to flow out at the discharge outlet. 40

The pump as a whole, is light, compact, cheaply constructed, and may be easily transported from place to place, or may be stored in small space.

45 The pump is especially adapted for marine work, on account of its light weight.

I claim:—

1. A hand operated pump, comprising a cylindrical casing having one end flaring 50 and provided with a discharge spout at the flaring portion, a plunger rod within the casing, said rod extending out of the casing

at the flaring end and having a handle, arms connected with the opposite end of the rod from the handle and extending longitudinally beyond said end, a ring rigidly connected with one arm and arranged coaxial with the plunger, a pivot pin rigid with the other arm and lying diametrically of the ring on the inner side thereof, a sectional valve consisting of approximately semi-circular flaps hinged to the pivot pin and normally lying on the ring, a sleeve engaging the end of the casing remote from the flaring end and extending beyond the casing, and having openings in its side wall, the upper end of the sleeve being cut away from each side inwardly and downwardly to the center of the said sleeve, a pivot pin arranged transversely of the sleeve at the junction of the said cut-away portion, a sectional valve consisting of approximately semi-circular flaps, said flaps being hinged to the pivot pin and normally resting on the cutaway edge of the sleeve, and means in connection with the sleeve for limiting the lifting movement of the said flaps. 60

2. A pump comprising a tubular casing provided near one end with a lateral outlet, a plunger rod within the casing and extending beyond the casing at the end adjacent to the lateral outlet, arms connected with the opposite end of the rod from the outlet and extending longitudinally beyond the said end, a ring rigidly connected with one arm, a pivot pin rigid with the other arm and extending diametrically of the ring on the inner side thereof, a sectional valve consisting of a plurality of flaps, each flap being hinged to the pivot pin and normally lying on the ring, a pivot pin held transversely of the casing at the end remote from the outlet, a sectional valve consisting of flaps hinged to the pivot pin, and a support for the last-named pivot pin detachably engaged with the casing and having means for holding the flaps in inclined position and having other means for limiting the lifting movement of the flaps. 80
